UNITED STATES PATENT OFFICE.

FREDERICK I. JOHNSON, OF BARRINGTON, RHODE ISLAND.

ELECTRIC ALARM.

No. 872,430.

Specification of Letters Patent.

Patented Dec. 3, 1907.

Application filed September 1, 1905. Serial No. 276,766.

To all whom it may concern:

Be it known that I, FREDERICK I. JOHNSON, a citizen of the United States, residing in the town of Barrington, county of Bristol, 5 and State of Rhode Island, have invented a new and useful Improvement in Electric Alarms, of which the following, with the accompanying sheets of drawings, is a description.

10 My invention is intended for use in hotels or other buildings where a number of lodgers may each wish to be called by an alarm at any hour and consists of a clock located in some central place connected by electric 15 wires with alarms and dials in the several rooms in the manner hereinafter described so that each lodger may set his dial at the hour at which he wishes to be called and when that hour arrives the central clock will 20 automatically make the proper electrical connections to ring the alarm in his room, without ringing other alarms not set for the same time.

In the accompanying drawings is illustrated a clock and connections sufficient for use at any quarter hour; but it will be apparent from the following description that the same principle can be readily used by a further duplication of wires and batteries at 30 as much more frequent intervals as desired. It is thought that quarter hour intervals will ordinarily prove satisfactory in practice.

In the drawings, Figure 1 shows my invention diagrammatically and the system of 35 wiring between the central clock and each room, including dials, bells, electric magnets, etc.; Fig. 2 represents the face of one of the dials located in one of the lodging rooms; Fig. 3 is a rear view of the dial with the cover 40 or back removed and showing the electric magnets and that portion of the wiring necessary to establish the connections by means of these magnets as will be more fully explained hereinafter; Fig. 4 is a side sectional view of 45 one of the dials showing the wires entering the rear of the dial and their distribution to the various contacts, magnets, and binding posts; Fig. 5 represents the rear of the clock shown in Fig. 1 and shows the wiring to 90 connect the contacts with the line wires; and Fig. 6 is an enlarged cross section of one of the hands and contact pieces and shows the projection attached to the hand for establishing the electrical connection between the

hand and the contact as well as the wire at- 55 tached to the latter.

The clock A. (Fig. 1),—see also Fig. 5,—is fitted with two sets of metallic contact pieces, one set twelve in number may form an inner circle under and in such a position 60 that they may be successively crossed by a projection b of the hour hand B., (Fig. 1), and will commonly form a complete circle, there being only sufficient spaces between them for the insertion of proper insulating 65 material. These contacts are indicated by the letter C. and the insulating material between them by C' (see Fig. 5). The other set of contacts are arranged in a circle outside the first set where they may be reached 70 and traversed by the projection d of the minute hand D., (Fig. 1). As shown in the drawings these latter contacts are four in number, one after each quarter of an hour and are indicated by the letter E. (Figs. 1, 75 4). As shown they are made of such a size that the minute hand will be three minutes in traversing each and consequently will cause the alarm to continue to ring for three minutes unless sooner shut off, as will be described later. It will be evident that these contacts may be made smaller or larger as desired, so as to shorten or lengthen the time of contact, and that they may be duplicated to any extent, the only limitation being that each must have its own wire to the 80 several rooms and each such wire its own battery.

The construction of the projection or attachment of the hands B. and D. as well as 90 the contact piece and the attachment of the wire to the latter is shown in Fig. 6 where W. may be considered as representing a cross section of one of the hands B. or D., X the projection or attachment made in the bent 95 form shown so as to always traverse the contact Y., and Z. the wire soldered or otherwise attached to the back of the contact.

In each room is a dial indicated by H. in Fig. 1 and shown by itself in Fig. 2. It has 100 two hands h and h' similar to those of a clock and which can be readily moved by the occupant. Under these hands are small contact points, one set of twelve in a circle to correspond with the hours, indicated by the letter 105 K., (see particularly Fig. 2), which are so placed that the dummy hour hand will come in contact with each as it is revolved. The

other set of four, indicated by the letter L., are placed to represent the quarter hours and are reached by the dummy minute hand which comes into contact with each as it is 5 revolved.

A set of twelve wires, numbered from 1 to 12 (both included) shown in Fig. 1, connect the twelve hour contacts of the clock with their respective twelve contact points upon 10 the dials, the wires being numbered in the drawings to correspond with the hour, and four other wires numbered 15, 30, 45 and 60 respectively connect the four quarter hour contacts of the clock with their respective 15 quarter hour contact points upon the dials. These wires, as also the two battery wires hereinafter described may be carried through the house and to the dials in the several rooms in cable form as indicated in Fig. 4. Inserted in 20 each of the four wires 15, 30, 45 and 60, is a battery to energize its wire when proper contacts are made, and each of these four wires is connected with the wiring of one of four electro magnets in each room.

25 A fifth battery is connected with its battery wire, marked N., and its return wire, marked R., with the alarm bell in each room and with the armatures of all the electro magnets in such manner that the circuit of 30 this bell battery will be closed whenever any one of the magnets is energized. The method of wiring the several dials with the bell wires and wires 15, 30, 45, and 60 will be understood from Fig. 3 where these wires are 35 supposed to enter the dial through the center hole, and the hour wires are omitted for the sake of clearness.

The wiring and the operation of the alarm will be understood by describing its action 40 as indicated in the drawings. It will be observed that four dials are shown in Fig. 1, each of which is supposed to be in a separate room of the house and they are marked Room 1, Room 2 etc. The hands of these 45 dials have been turned to the positions which would represent on a clock, a quarter past six, (room 1), half past six, (room 2), a quarter of six, (room 3), and six o'clock, (room 4), respectively, which are supposed 50 to be the times at which the occupants of the several rooms wish to be called. The central clock (Fig. 1) shows the time to be a quarter before six and therefore the circuits required to ring the alarm in the third room 55 should be closed, while all others remain open. The series of hour contacts C. C. on the central clock are preferably so arranged that the insulated spaces will occur where the hour hand will cross it between 30 and 45 60 minutes after the hour, since whenever it is desired to indicate a quarter before the hour, as a quarter of six, a person will commonly turn the dummy hands of a dial as in room 3 of the drawings by placing the hour hand on 65 the contact point for six o'clock so as to use

wire 6 instead of on that for five o'clock. In other words he will ordinarily think of a quarter of six instead of forty-five minutes past five. Accordingly the series of hour contacts C. C. of the clock in the drawings 70 are so arranged and at a quarter of six, wire 6 will be the one used for operating the alarm in room 3. The current flowing in the clock circuit at a quarter before six is indicated thus → and may be readily followed on wires 75 45, and 6 from the battery for wire 45 to contact for this wire on the central clock (see Fig. 6) through the hands of the clock and through the contact on the clock for the hour six and thence by wire 6 to the dial in room 80 3. It then passes through the dummy hands of the dial to the contact for 45 minutes and thence to wire 45, passes through and energizes the electro magnet in this wire 45 and thence back to the battery. It will be observed that the clock circuit in room 3 is the only one closed, since the hands of this dial are the only ones so set as to use wire 45 which is the wire with which the minute hand of the central clock is making the contact 90 to close the circuit. In other words the hands of the clock and the dummy hands of the dials must correspond before any clock circuit is closed.

The current flowing in the bell circuit is indicated by → and may be readily followed from the bell battery through the wire N. to room 3 where it is connected, as already described, with the bell and with the armatures of each one of the four electro magnets. 100 One of these four magnets, that in wire 45, is the only one energized and the only one which has attracted its armature into contact with its contact point to close the circuit. The current of this bell circuit therefore flows through the bell and this armature back to the battery. In the same way this current would flow through any one of the armatures in any one of the rooms whenever its electro magnet is energized so as to draw 110 it into contact with its contact point.

It is evident that the alarm will be sounded in all rooms set for the same time and in no others at that time. Wherever no call is wished, the dummy minute or hour hand of the dial in that room is so moved as not to be in contact with any of the contact points. Fig. 2 shows a dial with points for holding the dummy minute hand from revolving when it is set out of contact with any point to which wires are attached, and the hands as indicated in this figure are set not to ring the alarm.

A consideration of my invention and its method of operation will show that it enables me to add dials in an unlimited number of further rooms without increasing the number of wires because of such addition.

I claim as my invention;

1. A system of alarms consisting of a cen- 130

tral clock provided with contacts traversed by its hands, dials with contacts corresponding to those of the clock and means for connecting the dial contacts, and wires and batteries connecting the contacts of the clock with those of the dials; the clock hands, wires and batteries and connecting means of any dial forming a number of circuits one of which is closed whenever the hands of the 10 clock indicate a time for which the contacts of that dial are connected; a group of relay magnets for each dial, one of which is inserted in each of the clock circuits for that dial; and an alarm circuit with its battery 15 connected to the several relay magnets and including a bell for each dial, whereby the bell will be sounded whenever any one of the clock circuits for that dial is closed.

2. In an alarm, a clock having two sets of 20 electrical contacts, one traversed by the hour hand and the other by the minute hand, the hour and minute hands being in electrical contact, a series of dials having two series of

contact points, movable means for each dial to make electrical connections as desired between the two sets of contacts of that dial, 25 two sets of wires, one set connecting each one of the contacts traversed by the hour hand of the clock with the corresponding contact of all the dials, and the other set of wires connecting each one of the contacts traversed by the minute hand of the clock with the corresponding contact of all of the dials, an electro magnet for each dial inserted in each of one set of wires, an alarm and a circuit to 30 operate the alarm connected with the armatures and their contacts in such manner that the alarm circuit will be closed whenever any of the magnets are energized, and suitable electrical means for energizing the several 35 circuits.

FREDERICK I. JOHNSON.
